GAS LIGHT

Stanley M. Loveless, Kalamazoo, Mich., assignor to
General Gas Light Company, Kalamazoo, Mich.

Filed June 17, 1974, Ser. No. 479,779

Term of patent 14 years

Int. Cl. D26—05

U.S. Cl. D48—4 B

FIG. 1

FIG. 2

FIG. 3

FIG. 4

FIG. 1 is a side elevational view of a gas light embodying my new design;

FIG. 2 is another side elevational view of the gas light embodying my new design with same being taken from a different position as compared to that of FIG. 1;

FIG. 3 is a top plan view of the gas light; and

FIG. 4 is a bottom plan view thereof.

I claim:

The ornamental design for a gas light, as shown and described.
